CAN OPENER

Edward Zumski, Chicago, Ill., assignor to Ekco Products Company, Chicago, Ill., a corporation of Illinois

Application July 27, 1946, Serial No. 686,643

9 Claims. (Cl. 30—9)

1

The present invention relates generally to improvements in can openers, and has particular reference to can openers provided with a swinging frame supported for movement into and out of operative position, and with a cutting blade and feed wheel adapted to be brought into and out of cutting association.

One of the objects of the invention is to provide a can opener of the foregoing character in which the swinging frame is adapted to be automatically locked in operative position upon movement of the cutting blade and feed wheel into cutting association, and to be released for free swinging movement upon retraction of the blade from the wheel.

Another object is to provide the can opener with locking means available also to secure the swinging frame in idle position.

A further object is to provide a can opener of the foregoing character having a single actuating element for moving the cutting blade and feed wheel selectively into and out of operative association, and for locking and releasing the frame respectively against and for swinging movement.

A general object is to provide a new and improved can opener of the swinging-wall type which is simple, sturdy and inexpensive in construction, and which is efficient and reliable in operation.

Other objects and advantages will become apparent as the description proceeds.

In the accompanying drawings,

Figure 1 is a plan view of a can opener embodying the features of the invention.

Fig. 2 is a side elevational view.

Fig. 3 is a longitudinal vertical sectional view taken substantially along line 3—3 of Fig. 1.

Fig. 4 is a transverse vertical sectional view taken along line 4—4 of Fig. 2.

Fig. 5 is a transverse vertical sectional view taken along line 5—5 of Fig. 3.

Fig. 6 is a transverse vertical sectional view taken along line 6—6 of Fig. 3.

Referring more particularly to the drawings, the can opener, constituting the exemplary embodiment of the invention, comprises a main frame 1 adapted to be pivotally secured to a wall bracket 2 for swinging movement, preferably horizontally, either into an idle position parallel to and closely along a supporting wall 5, or into an operative position perpendicular thereto. In the specific form disclosed, the wall bracket 2 has a mounting base 3 adapted to be rigidly secured, as by means of screws 4, in flat engagement with the wall 5, and is bifurcated to provide two vertically-shaped parallel outwardly extending legs 6 and 7.

2

In order to provide substantial spacing, one of the screws 4 is located between the legs 6 and 7, and the other extends through a depending lug 8 on the base 3 below the leg 7. The pivoted end of the main frame 1 is formed with a rounded bearing 9 which is inserted with a snug fit between the legs 6 and 7. A pivot pin 10 is inserted vertically through suitable registering openings in the legs 6 and 7 and bearing 9 to complete the pivotal connection.

Suitably mounted in the free outer end of the frame 1 at the cutting side is a corrugated or serrated feed wheel 11 for engaging beneath the upper rim of the can to be opened. The wheel 11 is fixed on one end of a shaft 12 journaled in and extending through a transverse bore 13 in the frame 1. A hand crank 14 for rotating the wheel 11 is secured to the other end of the shaft 12.

20 A secondary frame or carrier 15, supporting a rotary cutter 16, is mounted on the main frame 1 for reversible movement either to locate the cutter in shearing relation with the feed wheel 11 or to retract the cutter therefrom.

25 More particularly, the main frame 1 is formed along the top with spaced parallel upstanding side wall extensions 17 and 18 defining a longitudinal groove 19 in which the secondary frame 15 is movably disposed. Preferably, the secondary frame 15 is elongated and of inverted U-shape in lateral cross section, and is supported with its side legs 20 in close interfitting and sliding relation with the wall extensions 17 and 18.

To provide means for movably interconnecting the frames 1 and 15, the frame 1 is formed with a longitudinal slot 21 opening downwardly therethrough medially from the groove 19 between the extensions 17 and 18. In the present instance, the slot 21 is flat-sided, and in alignment with

40 and substantially equal in width to the space between the side legs 20 of the frame 15. Link means, anchored within the slot 21, serves to constrain the frame 15 for arcuate movement, with a component longitudinally of the frame 1, as the cutter 16 is moved into and out of operative position. Preferably, the link means comprises a plurality of parallel links 22, two in the present instance, which are pivotally connected at their lower ends within the slot 21 by means of suitable

45 pivot pins 23. The upper ends of the links 22 extend into the secondary frame 15, and are pivotally connected to the side legs 20 thereof by means of pivot pins 24. By reason of the parallel link connection, the frame 15 is always maintained parallel to the frame 1 in all positions of movement.

Normally, the secondary frame 15 is urged yieldably away from the frame 1, i. e., upwardly

and forwardly along an arcuate path, toward and into open retracted position, as by means of a coiled compression spring 25. In the specific form shown, the spring 25 is seated at opposite ends in substantially aligned pilot bores 26 located respectively in the adjacent surfaces of the frames 1 and 15 at their extreme outer ends. Preferably, the holes 26 are so located that the spring 25 is inclined in the general direction of the opening and closing frame movements.

Any suitable means may be provided for moving the secondary frame 15, with the cutter 16, against the resistance of the spring 25, into closed position, and for releasably locking the frame in such position. In the present instance, this means comprises a rotary cam or eccentric 27 having an operating hand lever 28, and being pivotally connected to the frame 1 and arranged to bear against the top of the frame 15. More particularly, the eccentric 27 is bifurcated to receive, and is pivotally connected by a pin 29 to the upper end of, a vertical post 30 extending from the outer end portion of the frame 1 through a slot 31 in the frame 15. The slot 31 extends longitudinally of the frame 15, and is of sufficient length to permit the opening and closing movements thereof. Preferably, a similarly slotted wear plate 32 is set as a loose insert in the top wall of the frame 15 for direct bearing engagement with the eccentric 27. The face of the eccentric 27 is so curved that after movement of the frame 15 into fully closed position, as determined by abutment with the top of the frame 1 between the wall extensions 17 and 18, engagement with the wear plate 32 will be effected at a locking angle to maintain the cutter in operative position.

One of the important features of the invention is to provide means for automatically locking the frame 1 in operative position simply as an incident to movement of the cutter 16 into cutting position. This means utilizes the inner end of the frame 15 as a locking plunger 33 which will be projected into or retracted out of interlocking engagement with the wall bracket 2 as a result of the longitudinal shifting movement of the frame. Thus, the upper leg 6 of the wall bracket 2 is formed in the outer end with a notch 34 in alignment with the plunger 33 when the frame 1 is swung outwardly into operative position, and adapted to receive the plunger when the secondary frame 15 is moved by the eccentric 27 in closed position. As a result, the can opener is automatically locked in position to prevent inadvertent displacement and to obtain rigidity whenever a can opening operation is being performed, and without necessitating any separate action by the user. When the cutter 16 is retracted, the can opener is automatically released for free swinging movement into idle position.

The plunger 33 is similarly available to retain the can opener releasably in idle position. When the can opener is swung into position alongside the wall 5, actuation of the eccentric 27 to close the frame 15 will project the plunger 33 inwardly toward the adjacent side of the wall bracket 2 sufficiently to prevent inadvertent outward swinging movement by reason of interference with the outer end of the leg 6.

The remote side of the notch 34 is extended longitudinally of the leg 6 to define a stop lug 35 adapted for engagement with one side of the plunger 33 to locate the can opener in operative position. It will be evident in this connection that the plunger 33 is retractable sufficiently to clear one side of the notch 34 so as to permit free

swinging movement of the can opener in either direction through approximately ninety degrees between idle and operative positions, but never sufficiently to clear the stop lug 35.

Preferably, the end of the plunger 33 is formed with a curved recess 36 which is arranged to receive and engage a rounded projection 37 on the root surface of the notch 34 when the plunger is projected into locking position, thereby assisting in centering the frame or carrier 15.

The cutter 16 may be of any conventional type, and is shown as a rotary disk blade flat on one side and provided with a conical face 38 on the other side for overlapping shearing engagement with the outer side face of the feed wheel 11. One side of the outer end of the frame or blade carrier 15 is provided with a lateral bearing lug or projection 39 which extends over the feed wheel 11, and which is formed in the outer end with a recess 40. A plate 41, located by a plurality of dowels 42 and removably secured in position by a screw 43, serves to close the outer side of the recess 40. The screw 43 extends through the recess 40, and serves also as a pintle for rotatably supporting the cutter 16 which is confined thereon against axial movement between the bottom of the recess and the plate 41. Cleaning of the cutter 16 and the recess 40 thus may be facilitated by removing the plate 41.

The pintle 43 is inclined to the horizontal at an angle corresponding to that of the conical face 38 so that the latter will be substantially parallel to the outer side face of the feed wheel 11 when in operative association therewith along a substantially radial line of contact. Preferably, and in order to improve the cutting action, the pintle 43 is also inclined in horizontal relation to the axis of the feed wheel 11 and shaft 12. In this instance, the inclination is relatively slight, for example approximately two degrees.

The frame members 1 and 15 are provided with various locating surfaces to assist in maintaining the can in proper position during the cutting operation. Thus, a laterally projecting lug 44 on the frame 1 extends outwardly below the feed wheel 11 to serve as a rest for the side of the can. The bottom surface 45 of the bearing projection 39 is flat, and adapted to rest against the top of the rim of the can. Particularly at the rear side of the cutter 16, the surface 45 acts as a guide to prevent rocking or tipping of the can.

In operation, the can opener frame assembly is swung horizontally from the idle to the operative position perpendicular to the wall 5. One side of the can to be opened is positioned against the lug 44 and with the underside of the bead in contact with the top serrations of the feed wheel 11. The lever 28 is then actuated to rotate the eccentric 27, thereby moving the frame 15 downwardly and rearwardly into closed position against the main frame. This movement of the clamp results simultaneously in punching the rotary cutter blade 16 through the top of the can to bring the blade and wheel 11 into shearing relation, and in locking the can opener assembly positively in operative position due to the engagement of the end of plunger 33 in the notch 34. After the cutting operation has been completed, the clamp 27 is rotated in the reverse direction thereby moving the frame 15 into open position to retract the cutter 16 from the feed wheel 11, and simultaneously retract the locking plunger 33 from the notch 34. The frame assembly may now be swung out of the way into idle position,

and locked against outward swinging movement by again moving the frame member 15 into closed position to project the plunger 33 into interfering relation with one side of the wall bracket 2.

I claim as my invention:

1. In a can opener, in combination, a wall bracket formed with a locking notch; a slotted main frame member mounted on said bracket for swinging movement; a slotted secondary frame member carried by said main frame member and movable longitudinally with respect thereto, the inner end of said secondary frame member being of proper size to engage said notch in said bracket; resilient means tending to separate said frame members; feeding means carried by one of said frame members; cutting means carried by the other frame member and adapted to coact with said feeding means; eccentric lever-type clamping means attached to one of said frame members, and adapted to move said secondary frame member against said main frame member and longitudinally into said notch for the purpose of simultaneously bringing said cutting and feeding means into operative engagement and locking said main frame against movement with respect to said bracket.

2. In a can opener, in combination, a stationary support, a main frame mounted on said support for swinging movement relative to said support about an upright axis, means for locking said main frame against swinging movement including a secondary frame supported on said main frame for movement relative to said main frame toward and away from said support and inter-engaging means on said secondary frame and support operable to prevent movement of the secondary frame in the direction of swinging movement of the main frame upon movement of the secondary frame toward said main frame, cutting means mounted on one of said frames, and feeding means mounted on the other frame, said cutting and feeding means being movable into operative position simultaneously with movement of the secondary frame toward said main frame.

3. In a can opener, as claimed in claim 2, including clamping means associated with said frames for moving said secondary frame relative to said main frame.

4. In a can opener, as claimed in claim 2, including means for normally urging the secondary member in a direction away from said support.

5. In a can opener, in combination, a stationary support, a main frame mounted on said support for swinging movement relative to said support about an upright axis, means for locking said main frame against swinging movement including a secondary frame supported on said main frame for movement relative to said main frame toward and away from said support and inter-engaging means on said secondary frame and support operable to prevent movement of the secondary frame in the direction of swinging movement of the main frame upon movement of the secondary frame toward said main frame, cutting means mounted on said secondary frame, and feeding means mounted on the main frame, said cutting and feeding means being movable into operative position simultaneously with movement of the secondary frame toward said main frame.

6. In a can opener, in combination, a stationary support, a notch in said support, a main frame mounted on said support for swinging movement relative to said support, a secondary frame having an end portion engageable with said notch, means connecting said secondary frame and main

frame adapted to provide limited movement of the secondary frame relative to the main frame toward and away from a position wherein said secondary frame is engageable with said notch, cutting means mounted on said secondary frame, feeding means mounted on the other frame, said cutting means and feeding means being movable into operative position simultaneously with movement of the secondary frame toward a position of engagement with said notch, means normally urging the secondary member in a direction clear of said notch, and clamping means associated with said frames for moving said secondary frame relative to said main frame.

7. In a can opener, in combination, a stationary support, a notch in said support, a main frame mounted on said support for swinging movement relative to said support, a secondary frame having an end portion engageable with said notch, means connecting said secondary frame and main frame including parallel links adapted to provide limited movement of the secondary frame relative to the main frame toward and away from a position wherein said secondary frame is engageable with said notch, cutting means mounted on said secondary frame, feeding means mounted on the other frame, said cutting means and feeding means being movable into operative position simultaneously with movement of the secondary frame toward a position of engagement with said notch, means normally urging the secondary member in a direction clear of said notch, and clamping means associated with said frames for moving said secondary frame relative to said main frame.

8. In a can opener, in combination, a stationary support, a notch in said support, a main frame mounted on said support for swinging movement relative to said support, a secondary frame having an end portion engageable with said notch, means connecting said secondary frame and main frame adapted to provide limited movement of the secondary frame relative to the main frame toward and away from a position wherein said secondary frame is engageable with said notch, cutting means mounted on said secondary frame, feeding means mounted on the other frame, said cutting means and feeding means being movable into operative position simultaneously with movement of the secondary frame toward a position of engagement with said notch, means normally urging the secondary member in a direction clear of said notch, and means associated with said frames for moving said secondary frame relative to said main frame including an opening in the secondary member, a post unitary with said main frame member projecting through said opening in the secondary member, an eccentric clamping lever pivotally secured to the projecting end of said post.

9. In a can opener as claimed in claim 2 wherein said secondary frame is supported above said main frame.

EDWARD ZUMSKI.
